UNITED STATES PATENT OFFICE.

ENNO H. AUGUST HABBERT, OF TROY, NEW YORK.

SLEEVE FOR SHIRTS.

1,175,750.

Specification of Letters Patent. Patented Mar. 14, 1916.

Application filed January 13, 1915. Serial No. 2,053.

To all whom it may concern:

Be it known that I, ENNO H. A. HABBERT, citizen of the United States, residing at Troy, in the county of Rensselaer and State 5 of New York, have invented certain new and useful Improvements in Sleeves for Shirts; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to improvements in shirts, and more particularly to the sleeve portion thereof.

The prime object of the invention is to provide means to prevent a cuff or wristband slipping relative to the sleeve of an 20 outer garment.

25 The invention comprehends improvements in the details of construction and arrangement of parts, which will be hereinafter described and particularly pointed out in the claims.

In the drawing:—Figure 1 is a perspective view of a sleeve of a shirt, illustrating the application of my invention. Fig. 2 30 is a similar view, but illustrating a wristband supporting a cuff. Fig. 3 is a detail section of a sleeve with the improvement applied.

Referring to Fig. 1, 1 indicates a shirt 35 sleeve formed with the usual slit 2, at the cuff or stiffened outer end, and a fixed cuff 3. The slit 2, extends from the outer end of the cuff to about the elbow, and adjacent the edges are facings 4, sewed on the sleeve. 40 The end of one of the facing strips is preferably slit at the elbow, as at 5, while the opposite end is closed, thus forming a pocket 6. In this pocket is a thin flat stiff strip 7, which may be rigid or flexible, preferably 45 the latter. The strip 7, is inserted in the slit 5, and is confined between the opposite end walls of the pocket, as shown in Fig. 3, the slit being located at one side of the end wall, as shown.

50 The strip 7, may be a permanent part of

the shirt sleeve, but for convenience in laundering the shirt, the slit is formed in the pocket, so that the strip 7 may be conveniently removed.

When the strip is in position, it maintains 55 the cuff in fixed relation to the end of the coat sleeve, hence when the arm bends at the elbow, the strip abuts against the elbow portion of the coat sleeve 8, and the shirt sleeve cannot creep up the arm, independent 60 of the coat sleeve. By placing the strip in the position described, the cuff will at all times be retained in fixed relation to the coat sleeve irrespective of the position of the arm.

The attachment is just as effective when 65 a detachable cuff is employed, this application of the invention being shown in Fig. 2.

The improvement holds the cuff in relative position irrespective of the movement of the arm.

70 What I claim is:—

1. The combination with a garment sleeve formed with a stiffened outer end and formed with a pocket extending from the stiffened portion to the elbow of said sleeve, 75 of a stiff strip of material in the pocket and engaging the end walls of the latter to prevent the sleeve creeping when the arm bends.

2. The combination with a garment sleeve formed with a stiffened outer end and formed 80 with a pocket extending from the stiffened portion to the elbow of said sleeve, the wall of the pocket having a slit to receive a stiff flexible strip of material, of a stiff strip of material in the pocket and engaging the end 85 walls of the latter whereby to prevent the sleeve creeping when the arm bends.

3. The combination with a garment sleeve of a strip of stiff material extending from the elbow portion of said sleeve toward the 90 outer end, whereby to prevent the sleeve creeping when the arm bends.

In testimony whereof I have signed my name to this specification in the presence of two subscribing witnesses.

E. H. AUGUST HABBERT.

Witnesses:
